ATTORNEY

UNITED STATES PATENT OFFICE.

GEORGE E. PUTNAM, OF EAST KANSAS CITY, MISSOURI.

OIL FILTER.

Application filed January 25, 1921. Serial No. 439,825.

To all whom it may concern:

Be it known that I, GEORGE E. PUTNAM, a citizen of the United States, residing at East Kansas City, in the county of Clay and State of Missouri, have invented a certain new and useful Improvement in Oil Filters, of which the following is a full, clear, and exact description.

The object of the invention is to provide a combined oil washing and filtering device for removing the fine particles of carbon and other foreign matter from used automobile engine oil, and of such simple construction and of so few parts as to be capable of economical manufacture, of great durability and of easy access for the purpose of cleaning.

The invention consists of a receiving tank centrally located over a washing and filtering tank and connected thereto by a supply pipe through which the used oil flows by gravity from said receiving tank to the bottom of a washing compartment in the lower part of the main tank, thence rising through a washing medium in which the flow of the oil is retarded by a series of intercepting plates to a filter partition in said main tank, through which partition said oil is forced into a clean oil storage compartment in the top of said main tank, as I will now proceed to explain and finally claim.

In the accompanying drawing illustrating this invention, in the several figures of which like parts are similarly designated:

Fig. 1 is an elevation in cross section of the device.

Fig. 2 is a cross section of the means provided for compressing the filtering material.

Fig. 3 is a plan showing one of the series of intercepting plates identical with each other, centrally perforated to slip over the supply pipe and with one or more perforations to provide for the passage of oil from one plate to another.

Fig. 4 is a cross section of said intercepting plate, and

Fig. 5 is an elevation in cross section of the complete assembly of parts removed from the container.

In Fig. 1, a receiving tank 1 is supported on a supply pipe 2 by a threaded connection 3. Said supply pipe extends down through the center of a main tank 4 and is supported on the base of said main tank by means of a yoke 5 fixed to said base, into which yoke said supply pipe is held by a threaded con-

nection 6. A perforated intercepting plate 7 is shown welded to the lower end of said supply pipe above the threaded connection 6 and a series of similar plates are welded to said supply pipe at equi-distant points, as shown, said series of plates being so arranged that none of the perforations 7' in adjacent plates coincide vertically with each other. A downturned edge 8 is provided on each plate to hold for an appreciable length of time a quantity of oil within the limits of said plate during the upward passage of said oil through the washing medium.

A perforated compression plate 9 is shown welded to said supply pipe and a series of renewable filter pads 10^a, 10^b, 10^c and 10^d, each pad consisting of a layer of short fiber cotton between two disks of cloth 11^a and 11^b, and centrally perforated, placed thereon and a second perforated compression plate 12, having a central hole of a size to loosely fit over said supply pipe, is placed on the top of said filter pads.

A threaded sleeve 13 is removably fixed to said supply pipe by means of a thumb screw 14 and a compression nut 15 is provided to work in conjunction with said sleeve by which means pressure may be applied to the top compression plate 12, thereby compressing said filter pads and forcing the filtering material laterally into the grooves 16^a and 16^b which are formed to extend around the sides of the main tank 4 and also into the grooves 17^a and 17^b, which are cut around the surface of the supply pipe 2, forming thereby a firmly anchored mass of filtering material and providing specific means for preventing any unfiltered oil from creeping along the vertical edges of the filter partition and leaking from the washing compartment 18 into the clean oil storage compartment 19.

Said grooves 16^a and 16^b are not of sufficient size to prevent the easy removal of the complete assembly (Fig. 5) from the main tank 4 after the thumb screw 14 has been released and the supply pipe 2 unscrewed from its supporting yoke 5.

A removable cover 20 for the receiving tank, a similar cover 21 slipping easily over the supply pipe 2 for the main tank 4, a faucet 22 for drawing off filtered oil, an air relief cock 23, a thermometer 24, a gauge glass 25, a faucet 26 for drawing off the surplus water, and an electric heater 27 for which, however, an ordinary submerged steam heat-

ing coil or other means for heating the contents of the device may be substituted, are shown at the points and for the purposes indicated.

- 5 To operate the device as an oil filter, water is poured into the receiving tank from which it passes through the supply pipe into the washing compartment of the main tank, rising therein until it reaches the bottom of the 70 gauge glass. Heat is then applied by means of an electrical connection to the heater, or otherwise, and after the temperature as indicated by the thermometer reaches about 120 degrees Fahrenheit, the oil to be filtered is 75 poured into said receiving tank in small quantities at short intervals of time, care being used to see that the temperature is not materially lowered thereby. A certain amount of water beneath each of the intercepting plates will be displaced by oil and in consequence the water level rises slightly, becoming stationary at a point midway in the gauge glass. During this operation the air imprisoned between the surface of the 80 water and the filter partition slowly escapes, either through the filtering material or through the air relief cock, said cock usually being opened for this purpose, and said air is replaced by the oil rising through the 85 washing compartment until the entire space between said water and the filter partition is filled with said oil. Additional oil now poured into said receiving tank forces washed oil through said filter partition with 90 a pressure dependent upon the height of said oil in said receiving tank and said pressure may be maintained by further addition of used oil into said receiving tank, the filtered oil being drawn from the clean oil 95 storage compartment by means of the faucet 22.

This operation may continue until the accumulation of foreign matter taken from the used oil becomes so great as to prevent 100 the passage of oil through said filter partition, at which time the entire assembly of parts (Fig. 5) may be removed, as herein-after explained.

As previously stated the device is easily 105 accessible for cleaning purposes for it is only necessary to detach the threaded sleeve 13 from the supply pipe 2, thereby releasing the pressure of the compression plate 12 against the filtering material and relaxing 110 the lateral pressure of said filtering material against the sides of the main tank 4, in which condition said supply pipe may be unscrewed from its supporting yoke 5 and the entire assembly (Fig. 5) may be removed 115 from said main tank, thus leaving no inaccessible spaces or pockets in said main tank or in said assembly where dirt and foreign substances might remain unnoticed.

A convenient method for removing said 120 entire assembly from said main tank is to

detach the threaded sleeve 13 from the supply pipe and unscrew said supply pipe from its supporting yoke, and then fill the receiving tank 1 with water. The pressure thus created is transmitted against the bottom area of the filtering material and this upward pressure may be sufficient to force the entire assembly out of said main tank. The principle involved is that of a hydraulic press inasmuch as in the condition described 125 the mass of filtering material corresponds to a movable piston.

By the construction described I produce a combined washing and filtering device in which, during operation, the water level remains constant and there is no danger of the water reaching and destroying the filtering material. In the exceptional case of excess water being poured into the receiving tank with the oil, such excess water would be immediately shown in the gauge glass 25 and could be drawn off by means of the faucet 26.

As here shown and explained the device is designed to reclaim used automobile engine oil by removing therefrom dirt and foreign substances which, being held in suspension in said oil, render said oil unfit for use, although as previously stated, the invention is applicable to other fluids of different structures and consistencies by providing suitable washing and filtering materials, or by variation of the initial pressure against said filtering material, or by changing the density of said filtering material.

It is a consideration of importance that in the construction shown and described the oil is broken up and forced to pass through the water a predetermined number of times and that an oil filter of convenient size may be constructed in which the oil is broken up and washed at least seven times as shown, before it passes through the filtering material for its final cleaning, and that the entire process of washing and filtering the oil is confined within a single main tank having no permanent partitions.

As previously stated the intercepting plates break up the oil into thin streams during the washing process and tests have shown this construction to be particularly advantageous by reason of the fact that a thin film of oil is constantly held underneath said intercepting plates, due to the higher specific gravity of the washing medium, and that said film of oil is constantly in motion, due to the constant upward passage of oil from the supply pipe through the perforations in said intercepting plates in volume equal to that volume constantly passing through the filtering material; therefore, said intercepting plates hold for an appreciable length of time a large amount of oil practically in water suspen-

sion, creating thereby a condition which has been shown to be particularly favorable for the precipitation of dirt and foreign particles in the used oil.

5 It will be understood that variations in construction are permissible within the principle of the invention and that the invention is not limited to any specific application thereof, and the claim hereinafter 10 made is to be understood accordingly.

What I claim and desire to secure by Letters-Patent is:

An oil filter comprising a receiving tank, a vertical supply tube within the tank having 15 its inlet at the top and an outlet at the bottom of the tank, a filter bed carried by the tube and coextensive with the cross sectional area of the tank whereby, when the filter bed is expanded, its edges will fit

tight against the inner wall of the tank, the filter bed being positioned intermediate the ends of the tank to divide the same into an upper chamber and a lower chamber, and a plurality of similar inverted, concavo-convex plates carried by the tube and located in the lower chamber, said plates being spaced from each other and from the walls of the tank, each plate constituting an oil trap, the plates each having an opening offset with respect to a complementary opening in an adjacent plate.

In testimony that I claim the foregoing as my own, I have hereto affixed my signature in the presence of two witnesses.

GEORGE E. PUTNAM.
